TUMBLER

George W. Temple, New York, N. Y., assignor to
 Victor Metal Products Corporation, Brooklyn,
 N. Y., a corporation of New York

Application January 12, 1938, Serial No. 184,593

5 Claims. (Cl. 51—164)

This invention relates to slug-conditioning means and particularly to mechanism for cleaning, polishing and lubricating disc-like slugs of soft metal such as tin or aluminum, from which slugs collapsible tubes are later extruded.

Customarily, collapsible tubes are formed from discs of such soft metal by the extrusion of the discs in a suitable press to cause the metal of the discs to flow upwardly about a suitably shaped 10 plunger or male die. If the slug from which the collapsible tube is thus extruded is not clean and comparatively smooth, the resulting collapsible tube is frequently defective. Furthermore, if the slug is not lubricated properly, either a defective 15 tube is formed or the tube, if properly extruded and formed, may stick to the die and prevent it from being removed easily.

The present invention therefore contemplates the provision of means for cleaning, polishing 20 and lubricating a quantity of slugs while permitting the simultaneous cleaning and polishing of one batch of slugs during the lubrication of another batch.

The invention further contemplates the provision of simple and efficient means whereby a 25 batch of slugs may be quickly and easily advanced for the next succeeding operation thereon and for final discharge from the device while automatically discharging the cleaning material, 30 dirt, dust, foreign matter and the excess lubricant, so that the slugs finally conditioned by the machine are in the proper state to be fed to an extruding press.

The various objects of the invention will be 35 clear from the description which follows and from the drawings, in which,

Fig. 1 is a front elevation of the extruding machine.

Fig. 2 is an end elevation of the same. 40 Fig. 3 is a vertical section of the tumbling barrel of the machine showing the gate between the compartments in open position to permit the gravitational advance of the slugs from one compartment to the next compartment or out of the 45 machine.

Fig. 4 is a similar view of the same showing the gate in its closed position.

Fig. 5 is a vertical section of the same.

In the practical embodiment of the invention 50 which I have shown by way of example, the frame 10 of any suitable shape supports the various instrumentalities of the machine such as the hopper 11 which is provided with an open top 12 into which slugs may be fed from a suitable receptacle such as the drum 13. Said drum is

hoisted to the top of the frame 10 and tilted to dump the slugs therefrom into the hopper. The chute 14 conducts the slugs by gravity from the hopper into the preferably conical or funnel-like end 15 of the tumbler 16. Said tumbler is preferably provided with a longitudinal shaft 17 arranged coaxially thereof and preferably passing therethrough in a position inclined to the horizontal, so that the tumbler is mounted with the slug entrance end 15 thereof raised above the discharge end. Said shaft 17 is suitably supported for rotation as by means of the bearings 18 and 19 carried by the frame.

The shaft 17 and the tumbler 16 mounted thereon, are preferably rotated continuously 15 though the rotation may be stopped, if found advisable when a new charge of slugs is added to the tumbler. The means for rotating the shaft comprises the gear 20 on the shaft 17 which meshes with a corresponding gear 21 on the shaft 22. 20 Also mounted on the shaft 22 is the pulley 23; driven as by means of the belt 24 and pulleys 25, by the motor 26. It will be understood that said motor may be readily controlled by means of a suitable switch, not shown, to start and stop the 25 motor when desired in a well-known manner.

As has been indicated, the tumbler 16 is divided into a plurality of compartments as 27, 28 and 29 arranged coaxially and end to end, a slug conditioning operation being preferably carried 30 out in each compartment. Three such compartments have been shown though it will be obvious that any number of compartments may be provided if desired. As best illustrated in Figs. 1 and 5, means are provided for supporting a gate 35 between the compartments and at the ends of the tumbler and also for connecting the parts of the tumbler walls together to form a unit. Said means comprises a pair of similar fixed and flanged discs 30 and 31 spaced slightly apart 40 and each provided with a hub as 32, 33 held to the shaft 17 by means of a suitable set screw 34. The hub 32 is connected to the rim or flange 35 of the disc 30 by means of the web 36, said web having a series of spaced openings 37 therein 45 (Figs. 3 and 5) separated by imperforate segmental portions 38. The disc 31 is provided with similar openings in its web registering with the openings 37.

Mounted for rotary movement between the 50 rings is the disc gate 40, said gate being loosely pivoted on the shaft 17 and provided with spaced openings 41 of slightly less area than those of the openings 37, which openings 41 are separated by the imperforate segments 42 of said disc. A 55

suitable handle as 43 projecting from the periphery of the disc is provided for easy manipulation of the gate 40 during the rotation of the tumbler. The gate may easily be swung from its position shown in Fig. 3, in which the openings 37 and 41 are in registration to the position of Fig. 4 in which the openings are out of registration and the gate is closed, and vice versa. Suitable fixed stops as 44 and 45 are secured to the outer surfaces of the discs 30 and 31 at the proper places to limit the rotary movement of the gate and to determine the fully opened and closed positions thereof.

On their inner surfaces, each of the outermost flanges of the discs is preferably provided with a suitable annular recess as 46 for the reception of the end part of the member 47 forming the outer wall or surface of the compartment 29, said member 47 being held in place in the recess by suitable screws, bolts or rivets. One end of the coarse wire screen member 48, forming the wall of the compartment 28, is similarly inserted into the recess 49 of the disc 31, the other end of said member 48 being similarly inserted into the corresponding recess of the next disc between the compartments 28 and 27 and being similarly held in place. It will be understood that the discs 50, 51 and 52 at the ends of the compartments or between the compartments are similar to the discs 30 and 31 and hence require no detailed description nor illustration.

The inner end of the conical part 15 is also suitably shaped to fit into a recess in the disc 50 which also receives the end of the wall member 47, it being understood that the disc 50 need not be provided with a gate but that the slugs may flow from the chute 14 into the funnel-like member 15 and directly into the compartment 29. The wall 53 of the compartment 27 is made of metallic screen material preferably slightly finer than the screen wall 48. Each of the wall members 47, 48 and 53 is provided with a suitable opening closed by a hinged door as 56, said door being provided with latch means as 55 to keep it closed during the tumbling operation but being readily openable to clean out each of the respective compartments, or to remove jammed or broken slugs therefrom.

In operation, a drum 13 filled with slugs is hoisted to the top of the frame 10 and tilted to discharge the slugs therein into the hopper 11, the slugs being fed by gravity through the chute 14 through the funnel 15 and into the compartment 29, the gate 40 at the left end of which, as viewed in Fig. 1, is closed. Suitable cleaning material such as sawdust or the like treated if desired to more efficiently perform its cleaning function, is inserted through the door 56 or through the open end 15 into the compartment 29. The door 56 having been closed, the motor 26 is started, causing rotation of the tumbler 16. The slugs within the compartment 29 are thereby tumbled with the sawdust or other material for a sufficient length of time to clean the slugs of impurities with which they may be coated such as metal particles, dust, grease or the like and to remove burrs from the slugs and to polish them. After the tumbling operation in the compartment 29 has been completed, the gate 40 is opened and the slugs and other material within the compartment 29 are permitted to flow by gravity into the screen compartment 28. The gate 40 may then be closed and another charge of slugs and cleaning material inserted into the compartment 29. The gate in the disc 51 being closed, the process

is repeated with the slugs in the compartment 29 and simultaneously the slugs in the compartment 28 are tumbled to complete the polishing thereof, the sawdust or other foreign matter, dust and dirt dropping out of said compartment through the openings of the screen 48. The operation in the compartments 28 and 29 is carried on for a sufficient length of time to clean and polish the slugs in the first compartment 29 and to complete the polishing of the cleaned slugs in the compartment 28. Thereafter, the gate in the disc 51 is opened to permit slugs from the compartment 28 to gravitate into the compartment 27. Similarly, slugs from the compartment 29 are advanced to the compartment 28 and the compartment 29 re-loaded. Suitable lubrication is poured through the screen 53 of the compartment 26 in the desired amount to lubricate the slugs in said compartment thoroughly while said slugs are being tumbled, the excess lubricant flowing out through the screen wall 53. Finally, the gate in the disc 52 is opened to discharge the cleaned, polished and lubricated slugs into a suitable receptacle 54.

It will be seen that during the cleaning operation in one compartment, another batch of slugs is being polished in the next compartment while the third batch of slugs in the last compartment is being lubricated and that all the operations may be carried on simultaneously in the various compartments while permitting the advance of one batch of slugs to the next compartment with ease and rapidity.

It will further be seen that I have provided a simple machine for conditioning metal slugs whereby all necessary operations upon said slugs may be carried out in a single machine.

While I have shown and described certain specific embodiments of my invention, I do not wish to be understood as limiting myself thereto, but intend to claim the invention as broadly as may be permitted by the state of the prior art and the scope of the appended claims.

I claim:

1. In a machine for conditioning soft metal slugs, an inclined shaft, means for rotating said shaft, a plurality of fixed discs each having a number of spaced openings therein secured to the shaft, said discs being arranged in pairs with the openings thereof in registration, a disc-like gate provided with similar openings arranged rotatably between the fixed discs of a pair, and a series of cylindrical members secured at their ends to the discs concentrically with the shaft, at least one of said members being foraminated.

2. In a machine for conditioning soft metal slugs, a series of compartments, gates providing communication between adjacent compartments, means for revolvably supporting the compartments in a position inclined to the horizontal, a hinged door forming part of the surface of each compartment, and a foraminated member forming the remaining surface of at least one of the compartments.

3. In a machine for conditioning soft metal slugs, a tubular member, means for supporting said member for rotation about an inclined axis, said member comprising a plurality of compartments, partitions provided with openings therein arranged between the compartments and on at least one end of the member, a movable gate for temporarily closing the openings in each of said partitions, and a door for each of said compartments.

4. In a machine for conditioning soft metal slugs, a tubular member comprising a series of

compartments arranged end to end, gates between said compartments, and means for supporting the tubular member for rotation about an inclined axis, whereby on the opening of a gate, the slugs in the compartment on one side of the gate gravitate into the next succeeding compartment.

5. In a machine for conditioning soft metal slugs, a revoluble inclined shaft, means for rotating said shaft, a first disc provided with spaced openings therein secured to the shaft intermediate the ends thereof, a second similar disc secured to the shaft in slight spaced relation to the first

mentioned disc, a third disc rotatably mounted on the shaft between the first and second discs, a handle on the third disc projecting beyond said discs and accessible for manual operation to cause the openings in said third disc to register with the openings in the first and second discs, said first and second discs each having an annular recess therein, said cylindrical compartment-forming members concentric with the shaft and each arranged with an end thereof in one of said recesses. 5

GEORGE W. TEMPLE.
